UNITED STATES PATENT OFFICE.

JOHN SCANLAN, OF POUGHKEEPSIE, ASSIGNOR TO HIMSELF AND DAVID HOIT, OF ALBANY, N. Y.

CAR-DOOR FASTENING.

SPECIFICATION forming part of Letters Patent No. 269,963, dated January 2, 1883.

Application filed September 23, 1882. (No model.)

To all whom it may concern:

Be it known that I, JOHN SCANLAN, of Poughkeepsie, in the county of Dutchess and State of New York, have invented an Improvement in Car-Door Fastenings, of which the following is a specification.

Robberies of freight-cars on railways are of frequent occurrence, and it has been found that the robber usually jumps on the freight-train while going comparatively slowly up grade, climbs upon top of the car, lies down, reaches over the side, drives a spike into the side of the car, lowers himself down thereby, and with a hammer breaks the hasp or catch holding the padlock, opens the door, passes in and closes the same after him, selects the articles wanted, opens the door and pushes them out at the spot pre-arranged with confederates, and jumps off.

To prevent robbery of this kind is the object of the present invention; and it consists in the combination, with the sliding car-door, of a bolt acting from the top of the car vertically so as to pass in behind the top corner of the door, and a lever above the top of the car for actuating such bolt, and means for securing the same in place. This device, being on the top of the car, can be seen by the conductor or engineer, and if the same is raised so that the door can be opened, it remains in an elevated position, because the bolt rests on the top of the door when open, and should the robber pass into the car the said bolt, being automatic in its action, locks the person into the car, making him a prisoner.

In the drawings, Figure 1 is an elevation of the upper part of a car-door and the bolting device, and Fig. 2 is a plan of the same.

The car is made in any usual manner. A portion of the side *a* and top *b* are shown. The door *c* rests at the bottom upon slideways, and usually is provided with rollers, and at the top there is the overhanging guide-rail *e*, that keeps the top of the door in place. A locking-hasp, *f*, upon the door and a staple, *g*, upon the door-frame are provided, as usual.

Upon the top of the car is a lever, *h*, pivoted at one end in the jaw *k*, that is firmly secured to the top of the car, and there is a bolt, *l*, connected at its upper end by a joint to the lever *h* and passing vertically, or nearly so,

through a mortise that is behind and above the back edge of the door, so that when the bolt is depressed it comes behind the door. When the bolt is raised it is above and may rest upon the top edge of the door as it slid along beneath it.

Any suitable locking device may be used for holding down the lever *h*. I have shown the jaw *m* and cross-bolt *n* adapted to receive a lock or seal. A hole may be made through the bolt to receive a pin that holds up the bolt when raised, so as to keep it out of the way while the car is being loaded up.

By the foregoing construction it will be evident that when the car-door is open or partially open the lever *h* will be in an elevated position, and can be observed by the engineer or train-hands, and will indicate that the door has not been closed or is partially open. If the robber succeeds in opening both fastenings and getting into the car, and to prevent detection he closes the door so that the lever *h* falls, the bolt, being automatic, holds the door and makes the robber a prisoner.

This improvement is also useful with empty cars, because the bolt keeps the car-doors closed and avoids the resistance to the movement of the train resulting from the wind entering the car when the door becomes open.

It will be evident that a handle, or a screw, or a link may be combined with the bolt in place of the lever for raising or lowering such bolt and forming a visible indication of the position of the bolt.

I claim as my invention—

1. The combination, with the sliding car-door, of a vertical bolt above the back part of the door, and mechanism above the car for operating such bolt, substantially as set forth.

2. The lever *h*, pivoted at one end above the top of the car, the bolt connected to the lever and passing vertically, or nearly so, in behind the door of the car, and means for locking the lever and bolt, substantially as set forth.

Signed by me this 21st day of September, A. D. 1882.

JOHN SCANLAN.
